UNITED STATES PATENT OFFICE.

GEORGE A. GREGERSON AND FRED O. GREGERSON, OF ROCHESTER,
MINNESOTA.

DESIGN FOR A NECK-YOKE HOOK.

SPECIFICATION forming part of Design No. 25,149, dated February 11, 1896.

Application filed December 23, 1895. Serial No. 573,159. Term of patent 14 years.

To all whom it may concern:

Be it known that we, GEORGE A. GREGERSON and FRED O. GREGERSON, citizens of the United States, residing at Rochester, in the county of Olmstead and State of Minnesota, have invented a certain new and useful Design for Neck-Yoke Hooks, of which the following is a specification, reference being had therein to the accompanying drawings.

10 In the drawings, Figure 1 is a plan view, Fig. 2 an end view, and Fig. 3 a front view, of our design.

This invention consists of a circular band *a*, flat on its inner side and rounded on its outer side, and having projecting centrally from one side a hook *b*, which is substantially round in cross-section and which curves outwardly and upwardly from the band. The band is provided with oppositely-extending 20 ears *c*, which are substantially semicircular in shape and are provided each with a round opening *c'*. As will be seen, the ears are formed on the band on opposite sides of the hook *b*. On the upper end of the hook *b* is

formed a horizontal bar *d*, which is largest in 25 diameter at the point *d'* where it connects with the hook and which gradually tapers from that point in opposite directions toward its rounded ends *d''*. The edges of the bar *d* are rounded off, as shown. The bar *d* is attached to the hook to the left of its middle, thereby rendering the portion projecting to the left of the hook only about one-half as long as the portion projecting to the right. As will be seen, the bar runs approximately 35 parallel with the ears *c*.

Having thus fully described our invention, what we claim is—

The design for a neck-yoke hook, substantially as herein shown and described. 40

In testimony whereof we affix our signatures in presence of two witnesses.

GEORGE A. GREGERSON.
FRED O. GREGERSON.
